INK BOTTLE STOPPER

Augustine M. Mazzarelli, Brooklyn, N. Y.

Application March 4, 1939, Serial No. 259,922

1 Claim. (Cl. 120—57)

The present invention relates to closures and stoppers used in conjunction with ink bottles for india ink and the like, generally used by artists and draftsmen in preparing mechanical working drawings, Patent Office drawings and the like, and has reference in particular to the style of stopper which has attached thereto a so-called ink dispensing and pen charging quill.

Persons skilled in the art to which the invention relates are fully conversant with what may be classified as the conventional ink bottle, the same being provided with a cork or stopper having a central depending quill and the quill having its lower end tapered and pointed to expedite placement of ink on and between the nibs of the conventional inking pen. In using the marketed arrangement I have discovered the need for a structurally refined and improved stopper and quill assembly.

More specifically stated, the gist of the improvement has to do with a redesigned quill-end, the construction and arrangement being such as to provide a combined receptacle or well and applicator element cooperable therewith.

The purpose of the invention is, obviously, to permit the quill to take up a more abundant supply of ink so that it may be expeditiously applied to the inking pen or other drafting instrument. In accomplishing this result I have evolved and produced a simple and economical construction aptly fitted for the purposes intended.

Other features and advantages will become more readily apparent from the following description and drawing.

In the drawing, wherein the preferred embodiment of the invention is illustrated, and wherein like numerals designate like parts throughout the views:

Figure 1 is a view showing the conventional ink bottle and illustrating the improved stopper and quill assembly as perfected in accordance with the principles of this invention.

Figure 2 is an enlarged fragmentary detail view showing the slotted or apertured end of the quill and illustrating to advantage the applicator tip and well or reservoir.

Figure 3 is a section at right angles taken on the line 3—3 of Figure 2.

Referring now to the drawing by distinguishing reference numerals, it will be observed that the conventional ink bottle is denoted by the numeral 4. Fitting removably into the neck of this is the closure 5. This is of suitable composition material. The plug-like stopper 6 telescopes into the neck and the knob is on the exterior. The

latter portion comprises a flanged abutment element 7 and a suitably shaped protruding crown portion 8. In practice it is desirable to color the features 7 and 8 to correspond to the color of the ink to facilitate selection and use of predetermined ink bottles.

The tubular quill of appropriate composition is indicated at 9 and has its shank portion 10 anchored in the stopper. The utility stem depends centrally from the stopper and the lower end is 10 chamfered and slotted as at 11. Instead of terminating in the customary point, the terminal end is revised in accordance with the auxiliary features shown to advantage in Figures 2 and 3. That is to say, I provide an integral lateral terminal 12, this being preferably disposed at an obtuse angle to the longitudinal axis of the quill proper. It has an applicator point 13 and side confining walls 14. At the juncture of the applicator and quill proper the parts are shaped 20 to provide a receptacle or well 15.

It is evident that the chief novelty resides, broadly stated, in a quill equipped stopper assembly wherein the portion of the quill projecting into the ink is provided with a well or dipper means to take up what may be called a surplus or abundant supply of ink. More specifically, the quill is provided with special adapter means defining the well and the pointed applicator, the latter being at an angle to facilitate flow of gravity of ink and to expedite application to the point or nibs of the customary dual shank inking pen. The claim is to be interpreted accordingly.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

In a structure of the class described, an ink bottle stopper having a tubular quill, said quill being provided at its ink take-up end with a pointed V-shaped applicator, said applicator being at an obtuse angle to the longitudinal dimension of the quill and the junctural portion of the applicator and body portion of said quill being fashioned to provide an ink receiving and holding dipper in the manner and for the purposes described.

AUGUSTINE M. MAZZARELLI. 55
